United States Patent Office

Des. 190,744
Patented June 27, 1961

190,744

COMBINED PICNIC TABLE AND SEAT UNIT

John W. Guice, Arlington, Ga., assignor to Sunshine Metal Products Company, Inc., a corporation of Georgia

Filed Nov. 27, 1959, Ser. No. 58,471

Term of patent 14 years

(Cl. D33—14)

FIG. 2

FIG. 1 is a side perspective view of a combined picnic table and seat unit showing my design; and

FIG. 2 is an end perspective view thereof.

I claim:

The ornamental design for a combined picnic table and seat unit, as shown.
